UNITED STATES PATENT OFFICE.

CLYDE S. PELTON, OF CLEVELAND HEIGHTS, OHIO, ASSIGNOR TO THE PERFECTION HEATER AND MANUFACTURING COMPANY, OF CLEVELAND, OHIO, A CORPORATION OF OHIO.

HEATER FOR MOTOR-PROPELLED VEHICLES.

Original application filed March 24, 1917, Serial No. 157,243. Divided and this application filed May 8, 1920. Serial No. 379,819.

To all whom it may concern:

Be it known that I, CLYDE S. PELTON, a citizen of the United States, residing at Cleveland Heights, in the county of Cuyahoga and State of Ohio, have invented a certain new and useful Improvement in Heaters for Motor-Propelled Vehicles, of which the following is a full, clear, and exact description, reference being had to the accompanying drawings.

This invention relates to motor propelled vehicles, and particularly to the heating of the same by the use of the exhaust gases from the engine which drives the same. The objects of the invention are the provision of a new mode of attaching the heating device to the exhaust system; the provision of improved and simplified means for attaching a heater to the rearward end of the vehicle; the provision of means for attaching the heater directly to the muffler in which the exhaust is silenced; while further objects and advantages of the invention will become apparent as the description proceeds.

25 This application is a division of my earlier application No. 157,243, filed Mar. 24, 1917.

In the drawings accompanying and forming a part of this application, Fig. 1 is a side view with certain parts broken away of a muffler with connections to the engine and attachments to the heater; Fig. 2 is an enlarged sectional view of the parts constituting the rearward end of the muffler; and Fig. 3 is an enlarged plan view of the parts shown in Fig. 2.

Describing the parts by reference characters, the muffler here shown comprises an outer cylindrical casing 1 having end fittings 2—3 secured thereto. The end fitting 2 has a central hub 4 which receives the exhaust pipe 5 leading from the internal combustion engine (not shown). The end fitting 3 is also provided with a central hub 6 for the reception of the flexible pipe 7 leading to the heater 8 which is carried by the vehicle floor 9. Running from end to end of the muffler inside the casing 1 is a central tube 10 which communicates directly with the hubs 4 and 6; and likewise secured to the heads is the longitudinal tube 11 which surrounds the tube 10 but is eccentric thereto, so as to leave an increased space 12 adjacent the lower wall of the casing. Carried by the rearward head 3 and projecting

a considerable distance into this space is the discharge pipe 13.

The forward end of the tube 10 is formed with a plurality of perforations 15 for the escape of the combustion products as is likewise the rearward end of the tube 11, thus affording not only a sinuous path for the combustion products, but also an air cushion at the rearward end of the tube 10 by which the impulses received through the pipe 5 are absorbed. By attaching the vehicle heater immediately to the rearward end of this pipe, the gases are obtained at their maximum temperature, the inertia of their movement tends to force them the more positively into the heater, while the proximity of the muffler to the rearward end of the car enables the attachment of the heater with the smallest possible amount of piping 7.

In order to control the action of the heater there is formed between the hub 6 and tube 7 a valve chamber 16 in which is mounted the butterfly valve 17 carried by the spindle 18 operated by the handle 19, this valve being shown open in full lines and closed by dotted lines in Fig. 3. When the valve is closed, the muffler operates in the same manner as the usual type of muffler in which the rearward head is formed without any central opening; when the valve is opened the action of the muffler is improved by reason of the decrease of back pressure consequent upon opening another outlet for the gas. The gas escaping through this new passage is cooled and silenced by the heater 8 which is of any suitable or desired type.

It will be understood that I do not restrict myself to any particular type of muffler or to any particular type or arrangement of controlling valve, or to any other particular feature except as recited in my claims.

Having thus described my invention, what I claim is:

1. In an automobile driven by an internal combustion engine, the combination of a muffler having a casing and a pair of heads and a plurality of longitudinal tubes arranged eccentrically one within the other between said heads and provided with perforations at opposite ends thereof, one of said heads having an inlet opening communicating with the interior of the inner tube at the end thereof adjacent the perforations therein and the other head having an out-

let opening communicating with the space between the casing and said outlet tube at the end nearest the perforations in said outer tube and said other head having a second opening communicating with the interior of said inner tube at the end thereof remote from the perforations therein, and a heater connected to said last opening.

2. In an automobile driven by an internal combustion engine, the combination of a muffler comprising a cylindrical casing and a central tube, said tube communicating directly with the exhaust pipe from said engine and having perforations in its wall adjacent its front end, a second tube surrounding said first tube and eccentrically arranged relative thereto inside said casing and having perforations adjacent its rearward end, a discharge pipe projecting into the space between said casing and said second tube, a pipe connection leading from the rearward end of said first tube, a heating device to which said last pipe is connected, and means for controlling the flow of exhaust gas through said last pipe.

3. In an automobile driven by an internal combustion engine, the combination of a casing provided at one end with a substantially central aperture and at the other end with a substantially central aperture and a substantially peripheral aperture; a central tube extending between the ends of said casing, surrounding at each end the central aperture in that end of said casing to thereby bring said central apertures into communication with the interior of said tube, and provided near one end with a plurality of perforations; an outer tube also extending between the ends of said casing, eccentrically surrounding said central tube, joining that end of said casing which is provided with the peripheral opening at a point inwardly of said peripheral opening so that said peripheral opening communicates with the space outside said outer tube, and provided at the end remote from the perforated end of said central tube with a plurality of perforations; means connecting the central aperture adjacent the perforated end of said central tube with the exhaust leading from said engine; and a heater connected to the other of said central apertures.

4. In an automobile driven by an internal combustion engine, the combination of a casing provided at one end with a substantially central aperture and at the other end

with a substantially central aperture and a substantially peripheral aperture; a central tube extending between the ends of said casing, surrounding at each end the central aperture in that end of said casing to thereby bring said central apertures into communication with the interior of said tube, and provided near one end with a plurality of perforations, an outer tube also extending between the ends of said casing, eccentrically surrounding said central tube, joining that end of said casing provided with the peripheral opening at a point inwardly of said peripheral opening so that said peripheral opening communicates with the space outside said outer tube, and provided with a plurality of perforations; means connecting one of said central apertures with the exhaust leading from said engine; and a heater connected to the other of said central apertures.

5. In an automobile driven by an internal combustion engine, the combination of an elongated intake chamber provided at one end with an inlet, at the other end with an outlet, and near the inlet end with a plurality of perforations; an elongated exhaust chamber provided at one end with an exhaust opening and near that end with a plurality of perforations; an intermediate chamber arranged to surround and connect the perforated portions of said intake chamber and said exhaust chamber; means connecting the intake opening of said intake chamber with the exhaust from said engine; and a heater connected to the outlet opening of said intake chamber.

6. In an automobile driven by an internal combustion engine, the combination of an elongated intake chamber provided with a plurality of perforations, at one end with an inlet, and at the other end with an outlet; an elongated exhaust chamber provided with a plurality of perforations and at one end with an exhaust opening; an intermediate chamber arranged to surround and connect the perforated portions of said intake chamber and said exhaust chamber; means connecting the intake opening of said intake chamber with the exhaust from said engine; and a heater connected to the outlet opening of said intake chamber.

In testimony whereof, I hereunto affix my signature.

CLYDE S. FELTON.
